Attorney

UNITED STATES PATENT OFFICE.

MIRRELL E. JONES, OF PRESCOTT, ARIZONA, ASSIGNOR OF ONE-HALF TO WILLIAM P. HASSETT, OF ASHFORK, ARIZONA.

CAR-DOOR HANGER AND DOOR.

Application filed February 2, 1922. Serial No. 533,613.

To all whom it may concern:

Be it known that I, MIRRELL E. JONES, a citizen of the United States, residing at Prescott, in the county of Yavapai and State of Arizona, have invented certain new and useful Improvements in Car-Door Hangers and Doors, of which the following is a specification, reference being had to the accompanying drawings.

10 It is the purpose of the present invention to provide a device of this character wherein the hanger comprises upper and lower tracks, a door or closure slidably mounted therein, together with means carried by the upper track for retaining the door or closure in place.

Another purpose is to provide a door or closure, which is durable, strong and substantial in every way, and capable of being 20 easily opened and closed without binding. Furthermore the present structure of door or hanger is easy to repair, since the abutments can be removed from the rear of the tracks, allowing the door or closure to be 25 removed from the rear.

Still another purpose consists in the provision of a door, wherein suitable means is employed, acting to prevent water from entering the door opening.

30 A further purpose consists in the provision of an automatic latch or lock, carried by the lower rail, acting to automatically fasten the door or closure, when the door is moved to a closed position.

35 A further purpose is the provision of an automatic latch or lock, the arrangement and construction of which, being such that the latch or lock may fall behind one of the lower rear rollers of the door, when the door 40 is moved to a closed position, and also including means for the reception of a seal, which retains the latch or lock in a locked position, in such wise that it cannot be depressed out of the path of the rear lower 45 roller of the door, unless the seal is broken.

A still further purpose is the provision of improved means for mounting the upper and lower rails on the side of the door, particularly the lower rail, and in such wise 50 that the latch or lock may be pivotally mounted between the rail and the car, the upper rail being arranged, not only to support the upper rollers, but also to act as means for retaining the door in position.

55 While the design and construction at

present illustrated and set forth are deemed preferable, it is obvious that as a result of a reduction of the invention to a more practical form for commercial purposes, the invention may be susceptible of changes, and 60 the right to these changes is claimed, provided they are comprehended within the scope of what is claimed.

The invention comprises further features and combination of parts, as will be herein-after set forth, shown in the drawings and 65 claimed.

In the drawings:—

Figure 1 is a view in side elevation of a portion of a box car, showing the improved 70 hanger and door as applied, and constructed in accordance with the invention;

Figure 2 is a vertical sectional view through the same on line 2—2, showing the upper and lower hangers, the rails, and 75 mounting of the latch or lock;

Figure 3 is a transverse sectional view on line 3—3 of Figure 1, showing the means for preventing considerable water entering the door opening, the arrangement and construction of said means being such as to permit the door to open without interference;

Figure 4 is an enlarged detail view in side elevation of the lower rear corner of the door and its hanger, and the latch or 85 lock mechanism, with the lower rail section, more clearly showing the lock or latch;

Figure 5 is an enlarged sectional view on line 5—5 of Figure 4, showing one of the supports for the lower rail; and 90

Figure 6 is a detail plan view of one of the plates 37.

Referring to the drawings, 1 designates a portion of a box car, which is provided with a door opening 2, and 3 and 4 denote upper and lower supporting rails, upon which the hangers operate. The upper hanger is angular in cross section, comprising the portion 5 which is fastened by suitable bolts or the like 6 to the car, the laterally outwardly projecting portion 7, which overhangs the upper edge of the door 8. The laterally outwardly protruding part 7 terminates in a downwardly extending flange 9, which overlies the outer face of 105 the door, in such wise as to retain the door in close position to the door opening. In fact the flange 9 prevents the door from tilting outwardly.

Secured by bolts 10 to the upper outer 110

face of the door are plates 11 which have lateral portions 12, terminating in the upstanding parts 13. These parts 13 have overhanging rectangular portions 14 for the reception 5 of the bolts 15. Mounted upon the bolts 15 are rollers 16, which ride upon the outwardly laterally extending portion 7, there being flanges 17 to engage the outer face of the flange 9 of the rail. Suitable washers 10 18 are mounted upon the bolts 15 between the rollers and the opposite portions of the hangers or plates 11.

The door 8 has its outer face reinforced by the intersecting diagonal strips or straps 15 of metal 19, and secured to the lower edge of the door is an angle bar or strip 20. This angle strip 20 engages the outer face of the door and the under edge. Secured to the vertical front and rear edges of the door 20 are angle strips 21 and 22 which engage the outer face of the door, and the front and rear edges thereof. The flange 23 of the angle strip 21 which engages the front edge of the door terminates flush with the inner face of the door, whereas the flange 24 of the angle strip 22 extends beyond the inner face of the door. Bolts 25 and 26 secure the angle strips 21 and 22 to the door, and secured to the inner face of the door adjacent its front edge is a metallic strip 27, the same bolts 25 which secure the strip 21 in position also secures the strip 27 in position.

Secured by bolts 28 and 29 to the body of the car are forward and rear angle strips 30 35 and 31, the lateral flange 32 and strip 30 engages the metal strip 27, and acts as means to shed and keep out the water from the door opening. The flange 24 of the angle strip 22 overlies the lateral flange 33 of the angle strip 31, also acting to shed and 40 keep out the water. It will be noted that the overlapping of the flange 32 with the strip 27, and the lapping of the flange 24 over the flange 33 are such as to permit the door to slide rearwardly to an open position. These overlapping flanges also act to limit the door or closure in its closing position.

Secured to the upper portion of the outer face of the door, immediately adjacent its upper edge is a strip of steel or iron 34. The angle pieces or bars 20, 21 and 22 and the strip 34 act to reinforce and strengthen the door.

It will also be noted that the upper ends 55 of the angle pieces or bars 21 and 22 and the upper ends of the strips 19 terminate short of the upper edge of the door, thereby leaving spaces or room as at 35 for the reception of the plates 11, which constitute the upper hangers. The strip 34 also terminates short of the front and rear edges of the door, to permit of the fastening of the plates or hangers 11.

Secured to the lower portion of the outer 60 face of the car by means of bolts 36 are plates

37, which have outwardly extending brackets 38. The outer portions of the brackets 38 are spaced from the plates 37, and act as supports for the lower track or rail 4. Suitable bolts 39 pass through the rail 4 and through the outwardly extending brackets and receive nuts 40, which secure the lower rail or track in place.

The lower ends of the angle strips or bars 21 and 22 and the lower ends of the reinforcing strips 19, and the ends of the angle bar or strip 20 terminate short of the lower, forward and rear edges of the door, thereby leaving room or spaces as at 41 for the reception of the lower hangers 42 of the door. 75 These hangers 42 have U-shaped portions 43 which straddle the lower portion of the door, there being bolts 44 which pass through the arms of the U-shaped portions, and hold the hangers in place. The lower portions of 80 the hangers are also U-shaped, and mounted in bearings of the arms 45 of the lower U-shaped portions of the lower hangers are bolts 46, which carry the lower door supporting rollers 47. These rollers are flanged on 85 their opposite ends, so that the rollers may straddle the lower rail or track, thereby acting to retain the door in position. The outwardly extending brackets of the plates 37, where they connect with each other have 90 their upper portions cut away as at 49, to permit the inner flanges of the rollers 47 to pass, during the opening and closing movement of the door.

Secured by bolts 49, 50 and 51 to the upper and lower rails or tracks, and to the body of the car at points between the upper and lower rails are angle plates or abutments 53, 54 and 55, which act to limit the door in its forward and rear movements. In fact the upper rollers engage the forward and rear abutments 53, while the lower rollers engage the forward and rear abutments 54, whereas the forward and rear edges of the door contact with the abutments 55, acting to limit the door in its forward and rear movements.

Secured to the outer face of the door are handles 56, which are disposed perpendicularly. These handles are arranged in such wise on the lower portion of the door as will permit them to be reached from the ground or platform. The handles 56 are U-shaped, and have lateral portions at their upper and lower ends, which are secured by bolts 57 to the door.

Bolted as at 58 between the lower rail and the side of the car is a block or support 59, of the latch or locking member 60. This block or support has its outer face recessed as at 61, and mounted in said recess on a pivot or fulcrum bolt 62 is the latch 60. The latch 60 is pivotally mounted so as to possess a short arm 63 and a long arm 64. The short arm 63 extends at an obtuse angle to 130

the long arm 64, so that the latch is gravity actuated, so as to cause the short arm 63 to fall in position behind the rear lower roller of the door, when the door reaches a closed position, thereby locking the door in place. When the latch gravity actuates, the short arm 63 moves through an opening 65 in the upper horizontal flange of the lower rail 4, the beveled edge 66 of the opening 65 acting to limit the latch or lock in its locked position. The recess 61 of the block 59 is of such construction as to permit the latch or lock to tilt. The depending flange of the lower rail or track 4 and the terminal 15 (which is weighted) of the latch or lock 60 are provided with elongated openings 67, which are designed to receive a sealed sheet metal strip 68, to prevent the latch or lock from being unlocked, until the seal is broken. The short arm of the latch has an opening 69, which may receive the shackle 70 of a padlock, which will prevent the operation of the latch or lock, unless the padlock (not shown) is unlocked or broken. In 20 fact either one or both of the seals may be employed, either separately or at the same time.

Obviously when the latch or lock is not sealed, the door may be moved to a closed 30 position, in which case the rear lower roller will simply ride over and depress the short arm 63 of the latch or lock, in order to permit the short arm to assume a position to the rear of the roller. A depression of the short 35 arm will permit the door to be moved rearwardly to an open position.

The handles 56 stand lengthwise of the door, to prevent the hands of the operator from being injured, when closing the door, 40 as they are intermediate the perpendicular edges of the door. Also the handles can be reached from the ground or from the platform, as they are placed suitable for either. Every time the door is closed it automatically fastens itself, and furthermore the latch or lock is so mounted and protected as to prevent the same from freezing. The latch or lock may be operated from a locked 45 position to an unlocked position by engaging the hand of the operator under the lower rail or track when applying pressure to the long arm of the latch, and by pulling upon one of the handles the door may be moved rearwardly to an open position. However when 50 the door is closed, the latch or lock may be sealed at either or both ends thereof as previously stated. It will be noted that the latch or lock is practically at all times out of sight, and is protected from the weather 55 and has no projecting parts to become accidentally broken off:

The door proper is cross braced, and the parts are substantial and well bolted together. Furthermore the angle irons about 60 the perpendicular and bottom edges protect

the door from chipping off at the corners, and will also act to obviate warping. The structure for rendering the door more or less waterproof is cheap, simple and easy to construct, and is not in the way when it is necessary to remove the door. 70

The invention having been set forth, what is claimed is:—

1. In combination with a car door mounting including tracks located above and below 75 a door opening and further including a door carrying rollers traveling along the tracks, latching means comprising an elongated latch bar pivoted intermediate its ends within the lower track and having one end projectable through an elongated slot in the track, the other end being weighted whereby the latch bar will normally gravitate into operative position with its active end extending in the path of travel of the rollers, 80 85 said latch bar extending longitudinally of and being enclosed within the track.

2. A car door latch comprising an elongated bar extending longitudinally of and pivoted within a track upon which travel 90 rollers carried by a door, the track being formed with a slot through which one end of the latch bar is projectable, the other end of the bar being weighted whereby to be disposed gravitationally in normal position 95 with its active end extending through the slot in the path of travel of the rollers.

3. A car door latch comprising an elongated bar extending longitudinally of and pivoted within a track upon which travel rollers carried by a door the track being formed with a slot through which one end of the latch bar is projectable, the other end of the bar being weighted whereby to be disposed gravitationally in normal position with its 100 active end extending through the slot in the path of travel of the rollers, the weighted end of the bar being formed with an opening and the track being formed with an opening with which said first named opening 105 registers when the latch is in operative position, said registering openings being adapted to receive a seal.

4. A car door latch comprising an elongated bar extending longitudinally of and pivoted within a track upon which travel rollers carried by a door, the track being formed with a slot through which one end of the latch bar is projectable, the other end of the bar being weighted whereby to be disposed gravitationally in normal position with its active end extending through the slot in the path of travel of the rollers, the active end of the bar being formed with an opening designed to receive the shackle of 110 a padlock whereby to lock the latch in operative position. 115

In testimony whereof I hereunto affix my signature.

MIRRELL E. JONES.
